UNITED STATES PATENT OFFICE.

HENRY BAUER, OF BUDAPEST, AUSTRIA-HUNGARY.

BOLT-RETAINER.

937,039.

Specification of Letters Patent. Patented Oct. 19, 1909.

Application filed October 12, 1908. Serial No. 457,376.

To all whom it may concern:

Be it known that I, HENRY BAUER, a subject of the King of Hungary, and residing at 66 Trabellacita, Budapest VI, Empire 5 of Austria-Hungary, have invented certain new and useful Improvements in Bolt-Retainers, of which the following is a full, clear, and exact specification.

I, HENRY BAUER, architect, of Budapest 10 in Hungary, do hereby declare the nature of this invention and in what manner the same is to be performed, to be particularly described and ascertained in and by the following statement:

15 The object of my invention is to improve and facilitate the fastening of whatever articles, as: parts of buildings, supports, machines, frames, signs and the like to walls or foundations or other pieces of stone, 20 brick, concrete, or other masonry, whose material affords not the possibility of immediate securing with screws or nails or the like.

The means used hitherto to this end: as 25 wooden plugs, or the tapered heads of screws, or wedges, fastened into holes of walls with the help of plaster or cement, lead or brimstone, are subject to many deficiencies and disadvantages. Even the newest wedge-screws and expansion-bolts, 30 combined with the diversely shaped coins, or split shells of metal, or corrugated sheet-metal, show many imperfections and especially this, that those wedges or slotted 35 shells are expanded divergently and pressed only at their ends against the walls of the hole.

The present invention affords to such wall fastenings a new means, which is easy to 40 fabricate and to use, and being, in its employing, pressed at its entire length to the walls of the hole, affords a far stronger fastening, without necessitating the use of plaster, cement etc.

45 The accompanying drawings, referred to hereinafter, represent this means of fastening in: Figure 1, showing the longitudinal section of a "mantled nut", with screw; Fig. 2, showing the same section of a "mantled screw", with nut; Fig. 3, showing the same of a "mantled plug", with screw; Fig. 4, showing the transversal section of the "undulated mantle", through I—I; Fig. 5, showing the same through II—II; Fig. 6, 50 showing the elevation of the "undulated mantle"; Fig. 7, showing the transversal

section of the angular form of the same; Fig. 8, showing the perspective view of the "undulated plate wedge".

As shown by the drawings quoted above, 60 this new means of fastening consists in a "mantle", or shell of plate (a. Figs. 1, 2, 3, 4, 5, 6, 7,) undulated in such manner, that the undulations being deeper at one end (Fig. 4) and shallower toward the other end 65 (Fig. 5) and all together flattened out at the edge, by this successive and continual decreasing of the depth of the undulations, the plate gets the shape of a wedge (Fig. 8.) and the inner hole of the cylindrically or otherwise formed "mantle" (Figs. 1, 2, 3,) of such plate is rendered conical. The equally conical nut (b. Fig. 1.) or shaft of the screw (c. Fig. 2.) being placed into this conical hole of the mantle, as shown in Figs. 1, 2, 3, the 70 whole "mantled screw" so combined, entered in a hole of the wall, cut or bored with the like width or diameter, may be fastened most securely in the latter, by turning the screw (d. Fig. 1) or the nut (e. Fig. 2.) Instead of the conical nut a rounded or angular wooden plug (f. Fig. 3.) can be used to 75 the same effect, by which plug the mantle may be also expanded and fixed in the wall and, by means of the screw (g. Fig. 3.), any 80 piece whatever may be secured to this plug. In a plain form and in pieces of suitable length and breadth, the so undulated plate, 85 may be used as an "undulated plate wedge", to various other fastenings. 90

Having now particularly described and ascertained the nature of my said invention and in what manner the same is to be used, I declare, that what I claim is:

1. A bolt retainer comprising in combination, a sleeve adapted to be inserted in a bore in the material and having open ends and a continuously closed wall, said wall being longitudinally corrugated with the corrugations relatively deep at the top of said 95 sleeve and becoming gradually more shallow at the lower end and merging into a flat surface at the bottom of said sleeve, a threaded bolt member projecting into said sleeve and provided with a portion engaging the part 100 to be anchored, and a wedge member having threaded engagement with said bolt member and frictional engagement with said sleeve.

2. A bolt retainer comprising in combination, a sleeve adapted to be inserted in a bore 110 in the material and having open ends and a continuously closed wall, said wall being

longitudinally corrugated with the corrugations relatively deep at the top of said sleeve and becoming gradually more shallow at the lower end thereof, a threaded member projecting into said sleeve and provided with a portion engaging the parts to be anchored, and a wedge member having threaded engagement with said bolt member and fric-

tionally engaging the corrugations of said sleeve.

In testimony whereof I affix my signature in the presence of two witnesses.

HENRY BAUER.
